DESIGN FOR A COOK STOVE

John R. Morgan, Oak Park, Ill., assignor to Sears,
Roebuck and Co., Chicago, Ill., a corporation of
New York

Application April 4, 1936, Serial No. 61,946

Term of patent 7 years

To all whom it may concern:

Be it known that I, John R. Morgan, a citizen
of the Republic of Guatemala, residing at Oak
Park, in the county of Cook and State of Illinois,
have invented a new, original, and ornamental
Design for a Cook Stove, of which the follow-
ing is a specification, reference being had to the
accompanying drawing, forming a part thereof.

The drawing is a perspective view of a cook
stove, embodying my new design.

The side of the stove which is not shown is
similar to the side shown in the drawing.

The two shaded portions shown at the bottom
of the back splash panel on opposite sides of the
central back panel represent cavities for receiving
the lids shown adjacent thereto.

I claim:

The ornamental design for a cook stove, as
shown and described.

JOHN R. MORGAN.
